PROTECTIVE LINING

Application filed February 23, 1928. Serial No. 256,306.

This invention relates to and comprehends an improved protective lining which serves as a wear-resisting surface for various purposes.

5 The invention primarily contemplates the wear-resisting surface or lining which is preferably designed for use in blowers employed for feeding powdered or pulverized abrasive substances, such as powdered fuel, 10 or the like.

It has been found in practice that the active faces of the blades in certain portions of the casing become scored and wear out within a very limited period of time due to the 15 abrasive action of the substance being fed thereby. In order to increase the length of life or usefulness of the surfaces subjected to such wear, the present invention aims to provide in said surfaces serrations which 20 form pockets which filled with the substance being fed thereby present in effect surfaces substantially completely protected by the substance which will be refilled thereby as the scoring is produced thereon.

25 More specifically, the invention contemplates the formation in the surface or lining applied thereto of substantially ratchet-shaped serrations within which the substance collects for the purpose specified.

30 Other objects of the invention reside in the comparative simplicity of construction of same, the economy with which the same may be produced and installed, and the general efficiency derived therefrom.

35 With the above recited and other objects in view, reference is had to the following description and the accompanying drawings in which there is exhibited one example or embodiment of the invention, while the appended claims define the actual scope of the 40 invention.

In the drawings—

Figure 1 is a fragmentary sectional view 45 through a blower equipped with a protective lining or surface constructed in accordance with the invention;

Figure 2 is a transverse sectional view therethrough;

50 Figure 3 is an enlarged fragmentary detailed sectional view.

Referring to the drawings by the characters of reference, 10 designates the casing within which the fan 11 is mounted for rotation, said fan having the usual radial blades 12. On the leading faces of the blades 12 lining elements 13 are provided, while on the portion of the interior of the casing 10 where the wear occurs a protective lining 14 is provided.

The lining elements 13 and 14 are formed 60 with substantially ratchet-shaped teeth 15 which define similarly formed grooves or serrations 16. The grooves or serrations constitute pockets which may either be previously filled with a packed-down substance or material which is to be fed by the fan, or which are allowed to fill up with said substance during the operation of the fan. When the substance S is deposited and packed down within the pockets, grooves or serrations, as clearly 65 illustrated in Figure 3, it is obvious that the said substance S is subjected to the scoring action of the substance being fed through the blower and that the scores caused by the substance being fed will be rapidly refilled. It 70 is, therefore, obvious that only the apexes of the teeth will be subjected to the wearing action so that practically all the wear falls upon the substance packed in the pockets.

What is claimed is:—

1. An apparatus including a member having a surface subject to wear by the abrasive action of comminuted material impinged thereagainst, said member having contiguous substantially V-shaped parallel grooves in 85 said surface for producing a protective covering consisting of aggregations of said material collected in said grooves.

2. An apparatus for handling material which tends to abrade the surfaces thereof against which it is impinged, said surfaces having contiguous grooved portions to constitute means for collecting and retaining aggregations of said material to minimize abrasion of the surfaces, said grooves each being defined by a straight wall and an inclined wall, the inclined wall of each groove terminating at the outer edge of the straight wall.

3. An apparatus including a member having a surface subject to wear by abrasive ac- 100

tion of comminuted material impinging thereagainst, said member having parallel grooves of gradually increasing width from the inner portions to the outer end portions, the adjacent edges of the grooves being sufficiently close to each other to eliminate substantially the surface contour where the grooves are provided so that when said grooves have collected and retained aggregations of the material therein, the grooved portion of the surface will be protected against abrasion.

10 Signed at New York city in the county of New York and State of New York this 20th
15 day of February 1928.

JAMES D. O'BRIEN.
